PHILIP LAIR, OF PHILADELPHIA, PENNSYLVANIA, ASSIGNOR TO HAR-
TELL & LETCHWORTH, OF SAME PLACE.

Design No. 3,968, dated April 12, 1870.

DESIGN FOR SHADE FOR GAS OR LAMP-BURNERS.

The Schedule referred to in these Letters Patent and making part of the same.

I, PHILIP LAIR, of Philadelphia, county of Philadelphia, State of Pennsylvania, have invented and produced a new and original Design for a Shade for Gas or Lamp-Burners, of which the following is a specification.

The figure in the accompanying drawing represents in outline, a shade for gas or lamp-burners, made in accordance with my design, and consisting of the spherical or globe-like portion A, defined by the curved lines *a a* and upper horizontal lines *b*, and united at its base to the inverted frustum of a cone, B, defined by the inclined lines *c c* and flange *f*.

Irrespective of any ornamentation of the shade by grinding, cutting, coloring, or otherwise—

I claim the design for a shade, substantially as described, and as represented in and by the accompanying drawing.

In testimony whereof I have signed my name to this specification in the presence of two subscribing witnesses.

PHILIP LAIR.
